(57) CLAIM

The ornamental design for a oak leaf memorial marker, as shown and described.

DESCRIPTION

FIG. 1 is a front perspective view of an oak leaf memorial marker, showing the new design;

FIG. 2 is a front elevation view thereof.

FIG. 3 is a back elevation view thereof.

FIG. 4 is a right side elevation view thereof.

FIG. 5 is a left side elevation view thereof.

FIG. 6 is a top elevation view thereof; and,

FIG. 7 is a bottom elevation view thereof.

The broken lines in the drawings depict portions of the oak leaf memorial marker that form no part of the claimed design.
